[57] CLAIM

The ornamental design for a desk telephone set, as shown and described.

DESCRIPTION

FIG. 1 is a front, top and right side perspective view of a desk telephone set showing our new design in cradled relationship;

FIG. 2 is a front, top and right side perspective view of the stand, and a front, bottom, and left side perspective view of the handset spaced apart from the stand;

FIGS. 3 and 4 are respectively top and bottom plan views thereof;

FIGS. 5 and 6 are respectively front and rear elevational views thereof; and

FIGS. 7 and 8 are respectively right and left side elevational views thereof.

The cord is shown in truncated form in FIGS. 3-8 for convenience and simplification of illustration.

*Fig. 1**Fig. 2**Fig. 3**Fig. 4**Fig. 5**Fig. 6**Fig. 7**Fig. 8*
